(No Model.)

G. C. KEENE.

LOCK FOLD ATTACHMENT FOR CORNICE BRAKES.

No. 601,303.

Patented Mar. 29, 1898.

UNITED STATES PATENT OFFICE.

GEORGE C. KEENE, OF CINCINNATI, OHIO.

LOCK-FOLD ATTACHMENT FOR CORNICE-BRAKES.

SPECIFICATION forming part of Letters Patent No. 601,303, dated March 29, 1898.

Application filed August 7, 1897. Serial No. 647,430. (No model.)

To all whom it may concern:

Be it known that I, GEORGE C. KEENE, a citizen of the United States, residing at Cincinnati, in the county of Hamilton and State of Ohio, have invented a new and useful Lock-Fold Attachment for Cornice-Brakes, of which the following is a specification.

My invention relates more particularly to a supplemental lock-fold-forming attachment for use in connection with any of the well-known cornice-brakes, but preferably in connection with the cornice-brakes patented by me July 1, 1884, No. 301,128, and May 10, 1887, No. 362,749; and it consists in the novel feature of construction and combination of parts, such as are hereinafter fully described, and particularly pointed out in the claims.

In the accompanying drawings, Figure 1 is a transverse sectional elevation of a cornice-brake embodying my invention, taken on line $\alpha\alpha$ of Fig. 2 and showing a sheet of metal placed therein with the clamping-jaws open undergoing the lock-fold-forming operation; Fig. 2, a broken plan view of the movable platen or lower clamping-beam, showing my lock-fold-former devices thereon, the latter being also broken off, but showing sufficient for the purpose hereof; Fig. 3, an end view of the lock-fold-former gage-shaft, showing the eccentrically-arranged pin thereon, which constitutes its bearing, one being provided at each end of said gage-shaft; Fig. 4, an end view of a sheet of metal, showing a double lock-fold at either side, the result of an operation in my machine; and Fig. 5, a view similar to Fig. 4, but showing a sheet having a single lock-fold at either side.

A represents the supporting-frame leg at one end of the machine; B, the upper clamping or stationary tie-beam; C, the lower clamping or movable platen or beam, and D the bending-apron, journaling at its opposite axial ends d in boxes a on said platen.

E represents one of the several vertical push-bars whose lower ends pivotally engage the horizontal foot-shaft F at the base of the machine and whose upper ends pivotally engage the under side of the platen C, a foot-lever or treadle G being attached to the shaft F to operate it and the said platen. Spiral spring b is stretched between treadle G and an arm b' on the top of the frame-leg A to

augment the rising of the foot-treadle and the automatic opening of the clamping-jaws.

H represents a slotted circular plate on one end or axis of the bending-apron, and I a hand-lever for operating the latter.

c represents each one of a series of transverse arms or bars projecting laterally and forwardly from a longitudinal shaft d' over the platen C, with their free fore ends resting in suitable grooves made in the face of said platen. The said outer free ends of arms c are provided with upturned projections c' , (best seen in Fig. 1,) whose inner edges lie in a perpendicular line with the outer edge of the bending-apron, and the inner ends of said arms c are secured to forks on collars c^2 , which are in turn loosely mounted at suitable distances apart on the shaft d' , the latter having eccentrically-disposed pins or journals e constructed at its opposite ends, (best seen in Fig. 3,) which bear in bracket-boxes e' , projecting rearwardly from the platen near its opposite ends. (Best seen in Fig. 2.)

J is an arc or segmental arm attached to the platen C and projecting rearwardly from the latter near one end thereof. This arc is provided with a graduated series of openings or holes j for the reception of a stop or pin j' , which is removably placed in either hole to suit the different widths of folds in the sheets operated upon.

A forked hand-lever K is attached to the eccentric at one end of shaft d' , adjacent the bearing-bracket e' , and straddles the arc J for stop engagement with the pin j' . This hand-lever enables the operator to longitudinally move the gage-arms c to suit the different widths of folds to be made in the metal sheets.

In the operation of my special attachment the gage-arms c are simultaneously set (to suit the desired width of fold) by means of the handle K. Then a metal sheet S is laid thereon from the rear, with its fore edge resting against the upturned ends c' of said gage-arms. Then the foot-treadle is lowered so as to raise the platen C and thus firmly close the clamping-jaws (comprising said platen and the tie-beam B) on said sheet. Then the bending-apron is raised or turned on its axes by means of hand-lever I till the single bend or fold s is made in the edge of the sheet.

Then the foot-pressure is removed from the treadle, which permits the automatic opening of the clamping-jaws and the release of said sheet. The sheet passes through the 5 same movements for the fold along the other edge.

If it is desired to make a double fold s' in the edges of the sheet, as seen in the finished sheet, Fig. 4, the single-fold edge is inserted 10 up to the upturned ends c' of the gage-arms, as seen in Fig. 1. Then the clamping-jaws are closed and the same movements repeated as in making the single fold.

My lock-fold attachment is very simple and 15 effective and readily applied to a cornice-brake or removed therefrom without affecting the machine for other work.

I claim—

1. The combination with a cornice-brake, 20 comprising a pair of clamping jaws or beams, mounted on a suitable frame, and a bending-apron journaled on one of said jaws, of a lock-fold-forming attachment or gage device composed of a longitudinal shaft eccentrically 25 mounted at its opposite ends in bearings on the platen or moving jaw-beam, a series of gage-arms projecting laterally from the said shaft over said platen and having upturned outer ends against which the sheet is placed 30 for the fold-forming operation, and suitable

means for actuating said shaft to suit different widths of lock-folds to be made in the sheets, substantially as herein set forth.

2. The combination with a cornice-brake, 35 comprising a pair of clamping-jaws mounted on a suitable frame, and a bending-apron journaled on one of said jaws, of an adjustable lock-fold-forming attachment or gage device composed of a longitudinal shaft eccentrically mounted at its opposite ends in bearing-brackets on the platen or moving jaw-beam, a series of gage-arms projecting laterally and forwardly from said shaft over said platen and having upturned outer ends 40 against which the sheet is placed for the fold-forming operation, a hand-lever on said shaft, and an arc having a graduated series of holes therein for detachably accommodating a pin or stop to limit the throw of said hand-lever operating in connection therewith, and thereby, 45 adapt the attachment to different widths of lock-folds to be made in the various sheets, substantially as herein set forth.

In testimony of which invention I have hereunto set my hand.

GEORGE C. KEENE.
